UNITED STATES PATENT OFFICE.

HENRY SMITH DAGGETT, OF PUEBLO, COLORADO.

ROTARY ENGINE.

SPECIFICATION forming part of Letters Patent No. 591,328, dated October 5, 1897.

Application filed March 27, 1896. Serial No. 585,139. (No model.)

To all whom it may concern.

Be it known that I, HENRY SMITH DAGGETT, of Pueblo, county of Pueblo, and State of Colorado, have invented certain new and useful 5 Improvements in Reversible Rotary Engines; and I do hereby declare the following to be a full, clear, and exact description of the invention, such as will enable others skilled in the art to which it appertains to make and 10 use it, reference being had to the accompanying drawings, which form part of this specification.

My invention relates to an improvement in rotary engines; and it consists in certain 15 novel features of construction and in the combination and arrangement of parts, which will be fully described hereinafter and particularly referred to in the claims.

The object of my invention is to produce 20 an improved reversible rotary engine in which steam, gas, or compressed air can be applied with a constant flow and pressure on a set of buckets, and can be reversed at will, with the propelling fluid so confined as to gain the 25 highest efficiency.

In the accompanying drawings, Figure 1 is a vertical longitudinal sectional view, one side of the piston being illustrated in solid lines and the opposite side in dotted lines. Fig. 2 30 is a vertical transverse sectional view through the center of the engine. Fig. 3 is a vertical transverse sectional view of the piston. Fig. 4 is a plan view.

A designates the cylindrical casing, formed 35 with perforated lugs, and B are the opposite cylinder-heads, having perforated lugs alining with the cylinder-lugs and through which bolts *j* extend, and thus the cylinder parts are united in a most secure manner.

Piston C is journaled centrally in the cylinder and is formed with the two outside peripheral flanges *c* and the central flange *c'*, the three flanges having the same contour and fitting snugly within the cylinder in which 45 the piston rotates. Between the respective outside flanges *c* and inside central flange *c'* the periphery of the piston is formed with oppositely-disposed notches or steps to form the two series of buckets F F', the impact of 50 the propelling fluid upon the respective series serving to rotate the piston in reverse directions. Inlet-pipes D enter diametrically

opposite sides of casing A and pass the steam, gas, or compressed air, as the case may be, to the buckets F. Oppositely-arranged pipes D' 55 perform the same service for buckets F'. The respective pipes enter the casing in straight lines, so that the passage of the propelling fluid to the buckets is unobstructed, and the several pipes are arranged at such angles as 60 to aline with the long inner sides *f* of the buckets as they pass in succession the inlet ends of said pipes, so that the impact of the entering fluid is directly and unobstructedly against the angular abutment ends *f'* of the 65 buckets. Exhaust-ports E are formed on opposite sides of cylinder A, and the inner surface of the cylinder adjacent said ports is formed with depressions E', whereby the spent fluid may escape from either series of 70 buckets into said ports. The arrangement here shown and described has two oppositely-arranged fluid-inlets and two oppositely-arranged exhaust-ports, and as each of the bucket series is common to each exhaust- 75 port the fluid acts upon the piston during a quarter-rotation only of the latter when it exhausts. The frequent and rapid exhaust, combined with the double inlet for each series of buckets, render the engine capable of 80 high speed and great power.

The abutments *f'* of the buckets may be provided with attachable plates G, whereby the abutments are relieved of the wear incident to the direct impact of the fluid, the plates being so applied as to be readily removable when worn, so that others may be substituted. 85

The machinery or mechanism to be actuated may be connected in any suitable manner (not shown) to the central axial shaft K. 90

The engine is provided with a suitable base, which is secured by bolts I to a proper foundation.

Having thus fully described my invention, what I claim, and desire to secure by Letters 95 Patent, is—

1. An improved reversible rotary engine, comprising a piston centrally divided by a peripheral flange, a continuous series of buckets on each side of the flange, the buckets of one series arranged opposite to those of the other series, a casing in which the piston fits steam-tight and in which it is adapted to rotate, the flange of the piston dividing the casing into 100

two compartments, the inner wall of the casing being formed with exhaust depressions or cavities extending across the line of the central flange of the piston, whereby both 5 series of buckets are common to and adapted to exhaust in said depressions, and two inlet-ports for each series of buckets, two of the ports—one for each series—being arranged to simultaneously admit steam for rotating the 10 piston in one direction, the other two ports similarly coacting to actuate the piston in opposite direction, substantially as shown and described.

2. An improved reversible rotary engine, 15 comprising a piston formed with three peripheral flanges, a casing in which the piston fits and is adapted to rotate, the central of the three piston-flanges dividing the casing into two separate compartments, the inner wall of 20 the casing being formed on each side with a depression traversing the line of the central flange and into which each of the casing-compartments is adapted to exhaust, oppositely-

arranged series of buckets between the respective outer flanges and the central flange 25 of the piston, and two steam-inlet ports on each side of the casing, the ports of each side being arranged respectively above and below the exhaust-depressions, said two ports entering separate casing-compartments and 30 adapted to discharge steam against the abutments of the buckets, whereby in rotating the piston in one direction steam will be admitted in the upper inlet-port on one side of the casing and the lower port on the opposite side, 35 and vice versa for a reverse movement, the inlet-ports being arranged in lines substantially at right angles to the exhaust-depressions, whereby the steam acts on the buckets during a quarter-revolution of the piston 40 before exhausting, substantially as shown and described.

HENRY SMITH DAGGETT.
